UNITED STATES PATENT OFFICE.

JOSEPH SLADKY AND ALEXANDER C. SLADKY, OF MILWAUKEE, WISCONSIN, ASSIGNEES TO NATIONAL ENAMELING & STAMPING CO., INC., OF MILWAUKEE, WISCONSIN.

METHOD OF MAKING GENERATOR TUBES.

Application filed May 31, 1927. Serial No. 195,561.

This invention relates to a new and improved method for making generator tubes.

In generator tubes for gasoline stoves, it has been in usual practice heretofore to form these tubes in a manner which was relatively difficult to follow and which was expensive.

This invention is designed to overcome the defects noted above, and objects of such invention are to provide a novel method of forming a generator tube and a novel tube produced by such method which is free from any welded joints or other portions formed of different members, but which is integral throughout, and which although integral is nevertheless accurately shaped in accordance with the conventional contour of these generator tubes.

An embodiment of the invention is shown in the accompanying drawings in which:

20 Figure 1 shows one step in the process of making the tube;
Figure 2 shows the next step;
Figure 3 shows a successive step;
Figure 4 shows the finished tube.
25 Referring to the drawings, it will be seen that a tube 1 is cut to the desired length. This tube is formed of suitable material and of the requisite bore. The tube, after having been cut to length, is spun or otherwise formed adjacent one end to provide a constricted portion 2, or a portion of smaller diameter than the main body of the tube and to form a second or outer constricted portion 3 of still smaller diameter. The next step in the process of making the tube consists in accurately spinning or otherwise forming the portions 2 and 3 to the exact contours desired, as shown in Figure 3, and in tapping the hole 4 of the portion 2 and the hole 5 of the portion 3. If desired, these portions may be slightly bored out prior to tapping, although this operation may be dispensed with under ordinary conditions. Preferably, however, the bottom of the hole 4 is bevelled by a suitable boring tool to form a valve seat 6, as shown in Figures 3 and 4. It is to be noted that this valve seat is adjacent the portion joining the parts 2 and 3 and consequently leaves a web or in-

wardly directed small flange at the valve seat between the holes 4 and 5. The tube is also turned down at its outer end to provide the bevelled face or end 7.

The generator tube and valve is completed by screwing the end tip 8 into the hole 5, and by screwing the valve stem 9 into the threaded hole 4. It is to be noted that this valve stem is provided with a shouldered portion 10 which cooperates with the seat 6. The valve stem 9 is of sufficiently small diameter and is spaced from the inner walls of the tube 1, as shown in Figure 4. The bevelled outer end 7 of the tube enters the tapered aperture of the fitting 11. The fitting 11 is, of course, provided with an end cap 12 and an inlet portion 13 and the valve stem 9 is provided with the manipulating hand wheel 14. The valve stem 9, of course, may be provided with a needle point 15 adapted to project through the aperture in the tip 8 in the usual manner.

It will be seen that a novel form of generator tube has been provided by this invention in which the entire tube is integral throughout and does not have any welded joints or any portions in its major extent formed of different members.

It will be seen further that the generator tube is very readily produced in a cheap and rapid manner by the method described immediately above.

It will be seen further that the generator tube may be made from a very cheap stock, although it has the desirable characteristics enumerated above.

Although the invention has been described in considerable detail, such description is intended as illustrative rather than limiting as the invention may be variously embodied and as the scope of such invention is to be determined as claimed.

We claim:

The method of making a generator tube for a gasoline stove, said method comprising cutting a tube into predetermined lengths, forming one end of each tube length to provide a constricted portion with the interior of said tube from the restricted portion to one end

formed with an unbroken wall, forming a more constricted portion extending outwardly from said first mentioned constricted portion to the other end, tapping each of said constricted portions and leaving a web between said constricted portions, and forming a valve seat upon said web.

In testimony that we claim the foregoing we have hereunto set our hands at Milwaukee, in the county of Milwaukee and State of Wisconsin.

ALEXANDER C. SLADKY.
JOSEPH SLADKY.
